UNITED STATES PATENT OFFICE.

HOWARD E. GREEN, OF WESTERVILLE, OHIO, ASSIGNOR TO THE KILGORE MANUFACTURING COMPANY, OF WESTERVILLE, OHIO, A CORPORATION OF OHIO.

TOY SCALE.

Application filed April 15, 1927. Serial No. 184,040.

The present invention relates to toy weighing scales, and its purpose is to provide an attractive article of this nature with a minimum of moving parts with no possibility of disarrangement. The scale comprises a housing, an integral pointer and pendulum element, and an integral frame and pan. The transmitting connection between the beam and pointer is such that movements given to the one will be positively imparted to the other with no possibility of injuring or disengaging the connection, and this, of course, is the desirable feature considering that the device is intended primarily as a toy.

An embodiment of the invention is shown in the accompanying drawings wherein

Figure 1 is a side elevation of the scale.

Figure 2 is a section on the line 2—2 of Fig. 1.

Figure 3 is a top plan view.

Figure 4 is a perspective of the beam and integral pan, and

Figure 5 is a perspective of the integral pointer and pendulum.

Referring to the drawings, the scale housing is composed of front and rear castings 10 and 11 which by reason of interlocking lugs such as 12 are adapted to be held together by a single bolt 13, and by reason of abutting marginal flanges form a hollow body. These castings have respective upright portions which have been designated as 10 and 11, and horizontally extending portions 14 and 15. The horizontal portions have integral uprights or stanchions 16 and 17 respectively, and these are recessed at their tops to receive the knife edge bearings 18 and 19 formed integrally with and between beam 20 and pan 21.

At its free end beam 20 is provided with a counterweight 22 and a pin 23. The proportion of the parts is such that the center of gravity of the beam and pan is brought intermediate the knife edges and the pin so that considering the beam to be mounted on its supports, weight 22 will tend to move the pan upwardly.

As clearly shown in Fig. 2, beam 20 extends into the cavity between walls 10 and 11 through a suitable aperture formed by cutting away portions of the marginal flanges mentioned above. From the description thus far, it will be seen that the beam is mounted for pivotal movement about bearings 18 and

19 with its end projecting between the upright walls of the housing.

Mounted on bolt 13 for oscillatory movements is a pointer 23 provided with an aperture 24 through which the bolt extends. The pointer is extended downwardly beyond its pivotal point into an expanded portion 25 and a counter-weight 26. Portion 25 is provided with a cam slot 27 which extends at an angle of substantially 45° relative to the longitudinal line of the pointer proper. The oscillatory movements of the pointer are limited by the length of slot 27, so that it is permitted to swing through the vertical a certain extent in each direction. The counter-weight 26 and the weight of expanded portion 25 affect the balance of the pointer so that it is normally yieldingly urged towards its left hand limit of oscillation, as shown in Fig. 1.

Pin 23 of the beam, when the parts are assembled, engages a cam slot 27 and it will be seen that upon depression of pan 21 pointer 23 will be moved to the right against the force of counter-weight 22 and 26. In Figure 2 the space between walls 10 and 11 is shown as being so limited as to prevent disengagement of pin 23 from slot 27. Thus although the knife edges 18 and 19 can be lifted from their seats, the beam and pointer can never be disconnected as long as the casing elements are retained in operative relation.

Casing element 10 is provided with a window 28 and a scale of any desired character 29 is marked on the inner face of wall 11 in the usual relation to the pointer. Wall 11 is likewise provided with an arcuate window 29 so that the movement of the pointer is also visible from the rear of the housing.

From the above description it will be seen that the device is of the utmost simplicity, and thus extremely well adapted to its purpose. While a particular embodiment of the invention has necessarily been shown, it is to be understood that this showing is not to be taken as restrictive and that the scope of the invention is indicated in the following claims.

What I claim is:—

1. In a device of the class described, a pointer element mounted for oscillatory movements, a pivotally mounted beam element, one of said elements having a cam slot and the other a pin engaging in said slot whereby movements imparted to one of them

are positively transmitted to the other, said beam element being laterally expanded at one end to form a pan.

2. In a device of the class described, a pointer element mounted for oscillation within certain limits, a pivotally mounted beam element, connecting means between the beam and pointer elements whereby angular movements of the former are transmitted to the latter, and a counter-weight integrally formed on said beam element at one end thereof whereby said pointer element is normally yieldably held in a limit position, the other end of said beam element being laterally expanded to form a pan.

3. In a device of the class described, a pointer element mounted for oscillation, said element having a cam slot formed in an integral portion thereof, and a pivotally mounted beam element, said beam element having a pin engaging in said cam slot whereby angular movements of said beam element are transmitted to said pointer element.

4. In a device of the class described, a vertical pointer element mounted for oscillation, said element having a cam slot formed in an extension thereof below its pivot point, and a pivotally mounted horizontal beam element, said beam element having a pin engaging in said cam slot whereby angular movements of said beam element are transmitted to said pointer element.

5. In a device of the class described, a vertical pointer element mounted for oscillation, said element having a cam slot formed in an extension thereof below its pivot point, said slot extending at an angle of substantially 45° relative to the longitudinal line of said pointer, and a pivotally mounted horizontal beam element, said beam element having a pin engaging in said cam slot whereby angular movements of said beam element are transmitted to said pointer element.

6. In a device of the class described, a vertical pointer element mounted for oscillation, said element having a cam slot formed in an extension thereof below its pivot point, said slot extending at an angle of substantially 45° relative to the longitudinal line of said pointer, and a pivotally mounted horizontal beam element, said beam element having a pin engaging in said cam slot whereby angular movements of said beam element are transmitted to said pointer element to move the latter in the same angular direction.

7. Structure according to claim 4 wherein a counterweight is provided on the pointer

element below the cam slot to urge it yieldingly in one direction of oscillation.

8. Structure according to claim 4 wherein 60 a counterweight is provided on the beam element to urge it yieldingly in one pivotal direction.

9. Structure according to claim 4 wherein 65 counterweights are provided on both the beam and pointer elements to urge them yieldingly in the same angular direction.

10. In a device of the class described, an integral pendulum and pointer element mounted for oscillatory movements, a pivotally mounted beam element, and a cam slot and pin connection between said elements whereby movements of the one are positively transmitted to the other.

11. In a device of the class described, a 75 pointer element mounted for oscillation, a pivotally mounted beam element, a separable transmitting connecting means between said elements, and a housing having opposite walls positioned to maintain said connecting means 80 operative.

12. In a device of the class described, a pointer element mounted for oscillation, a cam groove in a portion of said element, a beam element fulcrumed on open bearings, a 85 laterally extending pin on said beam element engaging in said cam slot whereby movements of the beam element are transmitted to the pointer element, said pin being disengageable from said slot upon a relative lateral 90 movement of the two elements, and a housing having walls adapted to abut said elements to prevent such relative movement.

13. In a device of the class described, an integral pendulum and pointer element mounted for oscillatory movements, a pivotally mounted beam element, one of said elements having an integral part formed with a cam surface, and means on the other of said elements engaging said cam surface, whereby 100 weighing movements of said beam elements are transmitted to the pointer element.

14. In a device of the class described, a pointer element mounted for oscillatory movements, a pivotally mounted beam element, one of said elements having an integral part formed with a cam surface, and means on the other of said elements engaging said cam surface whereby weighing movements of said beam element are transmitted to said pointer 110 element.

In testimony whereof I have hereunto set my hand.

HOWARD B. GREEN.
